US0D1085314S

(12) **United States Design Patent** (10) **Patent No.:** **US D1,085,314 S**
(45) **Date of Patent:** **** Jul. 22, 2025**

(54) **FOLDING GUN**

(71) Applicant: **Magpul Industries Corp.**, Austin, TX (US)

(72) Inventors: **Nicholas Kielsmeier**, Denver, CO (US); **Michael T. Mayberry**, Denver, CO (US); **Zachary Freeman**, Broomfield, CO (US)

(73) Assignee: **Magpul Industries Corp.**, Austin, TX (US)

(**) Term: **15 Years**

(21) Appl. No.: **29/820,124**

(22) Filed: **Dec. 20, 2021**

(51) **LOC (15) Cl. 22-01**

(52) **U.S. Cl. USPC 22/104**

(58) **Field of Classification Search**

(57) **CLAIM**

The ornamental design for a folding gun, as shown and described.

DESCRIPTION

FIG. 1 is a front left top perspective view of a folding gun in a deployed configuration;

FIG. 2 is a left side view of the folding gun in FIG. 1;

FIG. 3 is a right side view of the folding gun in FIG. 1;

FIG. 4 is a front view of the folding gun in FIG. 1;

FIG. 5 is a rear view of the folding gun in FIG. 1;

FIG. 6 is a top view of the folding gun in FIG. 1;

FIG. 7 is a bottom view of the folding gun in FIG. 1;

FIG. 8 is a front left top perspective view of the folding gun in FIG. 1 in a folded configuration;

FIG. 9 is a left side view of the folding gun in FIG. 8;

FIG. 10 is a right side view of the folding gun in FIG. 8;

FIG. 11 is a front view of the folding gun in FIG. 8;

FIG. 12 is a rear view of the folding gun in FIG. 8;

FIG. 13 is a top view of the folding gun in FIG. 8; and,

FIG. 14 is a bottom view of the folding gun in FIG. 8.

The shade lines in the Figures show contour and not surface ornamentation.

The broken lines showing portions of the design in all figures are included for the purpose of illustrating environment and do not form a part of the claimed design.

1 Claim, 14 Drawing Sheets
